(57) **CLAIM**

I claim the ornamental design for an animal collar, as shown and described.

DESCRIPTION

FIG. 1 is a front view of the animal collar of my new design; FIG. 2 is a left side view thereof; FIG. 3 is a bottom view thereof; FIG. 4 is a top view thereof; FIG. 5 is a first perspective view thereof; FIG. 6 is a second perspective view thereof; and, FIG. 7 is a third perspective view thereof.

(Continued)

In the drawings, the broken lines depict portions of the animal collar that form no part of the claimed design.
